United States Patent Office.

THOMAS S. MITCHELL, OF PITTSBURG, PENNSYLVANIA.

Design No. 3,056, dated May 26, 1868.

DESIGN FOR A COOK'S STOVE.

The Schedule referred to in these Letters Patent and making part of the same.

TO ALL WHOM IT MAY CONCERN:

Be it known that I, THOMAS S. MITCHELL, of the city of Pittsburg, county of Allegheny, and State of Pennsylvania, have originated and designed a new Ornament for Cook-Stoves, of which the following is a full, clear, and exact description, reference being had to the accompanying drawings making part of this specification.

The drawings show a perspective view of the whole stove. In the general form thereof there is nothing new; it is an ordinary wood-burning cook-stove, having an oven, apron, ash-pan, and four holes on top for cooking purposes.

The doors are ornamented with a design in raised work, representing a shield, containing in its body thirteen stripes, and on the field or upper portion thereof are three stars. This shield is marked A on the drawing, and occupies the centre of each door. Around the edge of each door runs a moulding, shown on the drawing, and for the better understanding of which a sectional drawing is given, marked B.

I do not claim the general plan of the stove, for that is old.

Claim.

What I claim as my invention, and desire to secure by Letters Patent of the United States, is—

The design of the shield, marked A, and of the moulding, marked B, as shown on the drawing, circumscribed by the red lines *a*, *b*, *c*, and *d*, forming the ornamentation of the door of a cook-stove, substantially as shown and described in the drawings and specification.

THOMAS S. MITCHELL.
